MACHINE FOR MAKING PRINTED, CORRUGATED BOX BLANKS

Melvin H. Sidebotham, Winchester, Mass.

Application September 26, 1952, Serial No. 311,601

4 Claims. (Cl. 93—36)

1

This invention relates to paper corrugating machinery generally and particularly to machinery for making, from paper webs, double faced, printed, cut and creased container blanks.

Heretofore, so far as I am aware, the most common practice in effecting the production of such blanks has been to form double faced, corrugated, rectangular sheets, and thereafter crease, cut, and print the sheets to provide the required container elements. The printing operation being usually the final step. This requires much handling of the blanks with resulting high labor cost, and requires much operating space because separate machines are used and stock space is required close to each machine. The usual printing on corrugated blanks is of an inferior quality because the printing type must not be pressed hard against the blank or the corrugations will be crushed, thus damaging the blank.

One of the objects of my invention is to effect high speed production of printed, corrugated, paper, container blanks, by a sequence of operations comprising the feeding of three webs of paper, corrugating one web, securing the corrugated web to a second web, sometimes called a "face paper sheet," and printing a third web or face paper sheet and securing it to the opposite free side of the corrugated web to provide a printed, double faced, corrugated web. Thereafter, the web is to be creased and cut to provide container blanks.

Another object of my invention is to provide in a machine for making, from webs of paper, printed, double faced, corrugated, blanks, means whereby the mechanism for transversely cutting and creasing the blanks from the web may be adjusted while the machine is in operation to keep the cutting and creasing mechanism in register with the printing devices.

With said objects in view, and others herein-after explained, my invention consists in the method and machine, substantially as hereinafter described, and claimed.

Of the accompanying drawings:

Figure 1 is a side elevation illustrating the corrugating, combining and printing end of the machine.

Figure 2 is a side elevation illustrating the heating, cooling, creasing, cutting and delivery end of the machine.

Figures 1 and 2 taken together illustrate a side elevation of the complete machine, the left hand end of Figure 1 and the right hand end of Figure 2 are shown in the drawing as broken, but in the actual machine they are joined together and comprise one machine.

2

Figure 3 is a plan view of a section of web showing the result of the printing, creasing and cutting operations.

Figure 4 is a perspective view of one of the container blanks set up to form a container.

Figure 5 is an edge view, drawn to a scale larger than that of the other figures of the drawing, showing the corrugated material formed from the three webs.

10 Similar reference characters indicate similar parts or features in all of the views.

Referring first to Figures 1 and 2, the different parts or members of the machine are mounted on a suitable frame 1.

15 A roll of paper A for supplying the face paper web B is mounted on shafts 2, journaled in frame 1. The web of paper B is drawn uniformly and continuously from the said supply roll A by the action of feed rollers 3 and 4 journaled in frame

20 1. Positioned between feed rollers 3 and 4 is a heating drum 5 rotatably mounted on frame 1, the web B traveling over part of the outer diameter of the heating drum 5 in passing from roller 3 to roller 4. The purpose of the heating

25 drum is to heat the web B to condition it prior to its being combined with the corrugated web D hereafter described. The heating drum may be heated by any desired means, preferably by steam or electricity. From the feed roller 4 the web is advanced by rollers 6 and 7 journaled in frame 1 to engage the corrugated web D.

30 A roll of paper C, for supplying the web D which is to form the corrugated member, is mounted on shaft 8 journaled in frame 1. The web D is drawn from the supply roll by the rotation of corrugating rollers 9 and 10 which operate in the conventional manner to provide corrugations in web D. While the web D is still in contact with corrugating roller 10, suitable adhesive

35 is applied to the crowns of the corrugations on the web D by glue wheel 11 operatively mounted in glue pot 12 secured to frame 1. The further rotation of corrugating roller 10 causes the corrugated web D to engage the heated, face paper web B. The adhesive on the crowns of the corrugations on web D serving to secure the web D to web B to form a single faced corrugated web.

40 The heating of web B helps to dry or set the adhesive on web D when the two webs are brought together.

45 From the corrugating roller 10 the single faced corrugated web, made up of webs B and D, is drawn between endless conveyor belts 13 and 14. Belt 13 is driven by rollers 15 and 16 rotatably mounted on frame 1. Belt 14 is driven by rollers

50 17 and 18 rotatably mounted on frame 1. From

55 17 and 18 the web is delivered to the cutting and delivery end of the machine.

the conveyor belts 13 and 14 the single faced corrugated web is deposited on a slow moving endless conveyor belt 19, driven by rollers 20 and 21 mounted on frame 1. The conveyor belt 19 serves as a storage medium where the single faced corrugated web is deposited, and a supply accumulated. From the belt 19 the single faced corrugated web is picked up by roller 22 journaled in frame 1. From rollers 22 the composite web is advanced to rollers 23 and 24 journaled in frame 1. From roller 24 the single faced corrugated web is drawn between roller 25 and glue roller 26 journaled in glue pot 21 secured to frame 1. A glue roller 28 rotating in liquid adhesive in glue pot 21 serves to deposit adhesive on glue roller 26 which in turn deposits liquid adhesive to the crowns of the corrugations on the single faced corrugated web in preparation for adding thereto a second face web.

The second face web F is drawn from a supply roll E on shaft 29 mounted in frame 1. From the supply roll E the web F is advanced over rollers 30, 31 and 32 to a printing press base cylinder 33 operatively mounted in printing press base 34 secured to frame 1. The said cylinder 33 carries the web F against impression cylinder 35 where one color of printing ink is applied to the web, the web is next acted upon by impression cylinder 36 which in turn applies a second collar of printing ink to the web F. From the impression cylinder 36 the web F advances over rollers 37, 38 and 39 all journaled in frame 1. Between rollers 38 and 39 the web F is formed to provide a loop, with a dance roll 40 positioned in the loop to keep the web taut and to take up any possible slack in the web. From roller 39 the printed web is drawn by roller 41 journaled in frame 1, thence the web is advanced to contact the outside diameter of heated drum 42 journaled in frame 1. The drum 42 serves to aid in drying the printing ink so that the printed areas will not be marred by contact with other elements in subsequent fabricating operations. Roller 43 journaled in frame 1 serves to draw the printed web F from the heated drum 42 and advance it into position to engage the crowns of the corrugations on web D adhesively treated by glue roller 26. The web D having previously been combined with face paper web B to form a single faced corrugated web, then as previously explained, the crowns of the corrugations on the free side of the corrugated web D are treated with adhesive in preparation for receiving the printed web F which is brought into engagement with the web D and firmly pressed together by the action of endless, pressure and conveyor belts 44 and 45 supported and driven by rollers 46, 47, 48, 49, 50 and 51, all journaled in frame 1. While the belts 44 and 45 are advancing and pressing the webs B, D and F together to form a printed, double faced corrugated web, the composite web is carried through a heating unit 52 secured to frame 1, where the web is heated to further dry the printing ink, and also to dry the adhesive and drive off any excess moisture from the web. From the heating unit the web passes through cooling units 53 secured to frame 1. The cooling units are to quickly bring the web back to normal temperature.

The double faced, printed and dried web of corrugated paper board is next advanced to a web trimming device which acts to trim the longitudinal edges of the web, if necessary, to the desired size. The trimming operation is performed in the conventional manner by cooperating rotary tools 54 and 55 journaled in frame 1. From the

trimming device the web is advanced to be acted upon by creasing cylinders 56 and 57 rotatably mounted in frame 1, which serve to provide the longitudinal creases in the web.

The next operation consists in transversely creasing, cutting and severing the web to complete the production of individual container blanks.

The transverse web creasing, cutting and severing operation is effected by the rotation of cylinders 59 and 60. Secured to the outside diameter of cylinder 59 is a web severing knife 58 which operates to cut off a blank from the advancing web with each revolution of the cylinder. Also secured to the outer diameter of cylinder 60 at three points, spaced radially apart from the web severing knife 58, are creasing and cutting knives 61. The outer ends of knives 61 serving to cut the web, and the mid-portions of the knives, serving to crease the web.

The creasing and cutting cylinders 59 and 60 are operatively mounted in adjustable carrier unit base 62 supported on horizontally rotatable rollers 63 positioned on bracket 64 on frame 1. The cutting and creasing unit is adjustable horizontally by the action of screws 65 supported in adjusting brackets 64. Fastened to the outer end of each holding screw 65 is a crank handle 66. The screws 65 are operatively positioned in tapped holes in brackets 64. It will be obvious that by turning the crank handles 66, the carrier unit base 62 may be moved horizontally backward or forward as desired, to move the cutting and creasing cylinders 59 and 60 to the proper position in order that the advancing web may be creased, cut and severed in register with the printing on the web.

The adjustable feature of the carrier unit base is an important part of this invention, because in the production of articles from a web requiring cuts and creases to register with printed matter on the web, it is necessary to occasionally adjust the cutting and creasing devices in relation to the printing devices in order to correct any accumulated error resulting from unavoidable variations in materials and operating mechanisms. Therefore, when the machine here described is in operation the operator must watch the register of the cuts and creases with the printed matter on the web. If the cuts and creases creep out of register with the printing, the operator must move the carrier unit sufficiently to bring the cuts and creases into proper register. This can be done without stopping the operation of the machine.

After the completed blanks have been cut from the web, the blanks are delivered, by rollers 67 and 68 rotatably mounted in frame 1, to the delivery bin 70 situated adjacent to the delivery end of the machine.

Referring to Figure 3, which illustrates a section of the printed, double faced, corrugated web, the edges 71 represent the edges trimmed by rotary tools 54 and 55. The longitudinal dotted lines 72 represent the creased lines provided by creasing cylinders 56 and 57. The transverse dotted lines 73, and the transverse full lines 74, represent the creases and cuts respectively made by the action of knives 61 in cylinder 59. The full transverse lines 75 represent the cuts made by web severing knife 58 which operates to cut each blank from the advancing web. The printed matter on the web is represented by the numeral 76.

In the use of this machine, with each size of container to be made, materials of the proper

size are selected; that is, the width of the web supply rolls of paper is preferably of the required size in order to eliminate the trimming operation if possible. The creasing cylinders 56 and 57 are next adjusted to longitudinally crease the web as desired. Then the printing cylinders 35 and 36 must be prepared with the printing medium spaced so as to provide printing on panels of the container. The creasing and cutting cylinders 59 and 60 are likewise suitably changed preparatory to producing each size of container. The bracket 64 is adjustable horizontally, by means previously described, to register the cutting and creasing operations with the printing on the web. Thus, the length of web to be cut off from the advancing web to provide each box blank is determined and regulated by the horizontal position and make-up of the creasing and cutting cylinders 59 and 60.

It will be understood, without need of illustration that any suitable motor may be employed for operating the machine, and that suitable gearing is employed in practice to cause the various rolls to rotate at uniform peripheral speed to effect the travel of the webs through the machine in order that the operations of the several units thereof will be effected in the sequence described.

Having now described my invention, I claim:

1. A machine for making printed, corrugated, paper containers, comprising means for causing two webs of paper to travel; corrugating rolls for operating on one of the webs; means for applying heat to the other web and then adhesively connecting the corrugated web to the other web to provide a single faced corrugated web; an accumulator device; advancing means to convey the combined web to the accumulator device; means for causing a third web of paper to travel; a printing unit to print the third web; means to convey and guide the third web to a web heating device; a dance roll positioned to ride in a loop in the third web, between the printing unit and the third web heating device; an adhesive applying device for securing the printed third web to the free side of the corrugated web, to form a printed, double faced, corrugated web; means for advancing the printed, double faced, corrugated web; means for heating and then cooling the printed, double faced, corrugated web; cutting devices to trim the longitudinal margins of the printed, double faced, corrugated web; devices to apply longitudinal creases in the web; a cutting and creasing cylinder operatively positioned to transversely cut and crease the web; a horizontally movable base for supporting the cutting and creasing cylinder; a hand operated device for horizontally adjusting the movable base in its relation with the printing unit; and means for delivering completed blanks from the machine.

2. A machine for making printed, corrugated, paper containers, comprising means for causing two webs of paper to travel; corrugating rolls for operating on one of the webs; means for applying heat to the other web and then adhesively connecting the corrugated web to the other web to provide a single faced corrugated web; an accumulator device; means for causing a third web of paper to travel; a printing unit to print the third web; means to convey and guide the third web to a web heating device; a dance roll positioned to ride in a loop in the third web, between the printing unit and the heating device; an adhesive applying device for securing the printed third web to the free side of the corrugated web, to form a printed, double faced, corrugated web; 75

means for advancing the printed, double faced, corrugated web; means for heating and then cooling the printed, double faced, corrugated web; devices to apply longitudinal creases in the web; a cutting and creasing cylinder operatively positioned to transversely cut and crease the web; a horizontally movable base for supporting the cutting and creasing cylinder; a hand operated device for horizontally adjusting the movable base in its relation with the printing unit; and means for delivering completed blanks from the machine.

3. A machine for making printed, corrugated, paper containers, comprising means for causing two webs of paper to travel; corrugating rolls for operating on one of the webs; means for adhesively connecting the corrugated web to the other web to provide a single faced corrugated web; means for causing a third web of paper to travel; a printing unit to print the third web; means to convey and guide the third web into engagement with the single faced corrugated web; a dance roll positioned to ride in a loop in the third web, between the printing unit and the point of contact with the single faced corrugated web; an adhesive applying device for securing the printed third web to the free side of the corrugated web, to form a printed, double faced, corrugated web; means for advancing the double faced corrugated web; cutting devices to trim the longitudinal margins of the double faced corrugated web; devices to apply longitudinal creases in the web; a cutting and creasing cylinder operatively positioned to transversely cut and crease the web; a horizontally movable base for supporting the cutting and creasing cylinder; a device for horizontally adjusting the movable base in its relation with the printing unit; and means for delivering completed blanks from the machine.

4. A machine for making printed, corrugated, paper containers, comprising means for causing two webs of paper to travel; corrugating rolls for operating on one of the webs; means for adhesively connecting the corrugated web to the other web to provide a single faced corrugated web; means for causing a third web of paper to travel; a printing unit to print the third web; means to convey and guide the third web to contact the single faced corrugated web; a dance roll positioned to ride in a loop in the third web, between the printing unit and the point of contact with the single faced corrugated web; an adhesive applying device for securing the printed third web to the free side of the corrugated web, to form a printed, double faced, corrugated web; means for advancing the printed, double faced, corrugated web; devices to apply longitudinal creases in the web; a cutting and creasing cylinder operatively positioned to transversely cut and crease the web; a horizontally movable base for supporting the cutting and creasing cylinder; a device for horizontally adjusting the movable base in its relation with the printing unit; and means for delivering completed blanks from the machine.
